ATTORNEY.

UNITED STATES PATENT OFFICE.

HARLEY C. WOOD, OF CHICOPEE FALLS, MASSACHUSETTS, ASSIGNOR TO THE FISK RUBBER COMPANY, OF CHICOPEE FALLS, MASSACHUSETTS, A CORPORATION OF MASSACHUSETTS.

TRUCK.

Application filed May 15, 1925. Serial No. 30,431.

To all whom it may concern:

Be it known that I, HARLEY C. WOOD, a citizen of the United States of America, residing at Chicopee Falls, in the county of 5 Hampden and State of Massachusetts, have invented certain new and useful Improvements in a Truck, of which the following is a specification.

This invention relates to a truck especially 10 adapted for industrial use where strips of adhesive material, such as rubberized tire material, are to be piled and transported with interleaved sheets of a separating material such as cotton duck. The object of 15 the invention is the provision of a truck which may carry a maximum amount of the piled strip material, covering substantially its entire plane area, and yet which may at the same time carry a supply of lining material 20 always located in a convenient position for handling.

Referring to the drawings,

Fig. 1 is a perspective of an unloaded truck;

25 Fig. 2 is a plan of a loaded truck; and

Fig. 3 is an end elevation of a loaded truck.

The truck is carried on stringers 10 supporting a platform 11. Rollers 12 at the 30 rear end and casters 13 at the front make the truck portable. Arranged at the ends of the truck is a framework, comprising in the illustrated form uprights 14 connected by a channel iron 15. The two channel 35 irons 15 are preferably braced by a strip 16 which slants down to meet the platform 11 at its middle, thus performing the two functions of adding rigidity to the end frames and of dividing the truck longitudinally 40 into two halves. Running upon flanged rollers 17 upon the channel irons 15 is a movable platform 18, made long enough so that its ends will strike the uprights 14 and limit its possible range of movement.

45 In the use of the truck a pile of sheets of lining material 19 is kept on the movable platform 18, which is rolled to one side of the truck as shown in Fig. 3. As the sheets 20 of rubberized material are received, they 50 are placed in a pile upon the lower platform

11 at the opposite side of the truck from where the platform 18 is located, sheets of liner material being taken from the pile on the movable platform and interleaved with the rubberized stock to prevent adhesion of 55 the latter. When the pile on the lower platform has been built up to the desired height, which will be less than the height of platform 18, the movable platform is rolled over it, exposing the second side of the 60 main platform for further piling operations. In unpiling the material a reverse operation is followed, the sheets of separating material being taken off the pile on the lower platform and piled on the movable platform, while the sheets of rubberized material are removed from the truck. 65

Having thus described my invention, I claim:

1. A truck having a main platform, presenting a surface for piling material, a super-structure including a transverse track, and a platform substantially half the width of the main platform and mounted for lateral movement on said track from one side 70 to the other of the truck, said movable platform also presenting a piling surface.

2. A truck having a main platform, a super-structure including a transverse track, a platform substantially half the width of 80 the main platform and mounted for lateral movement on said track from one side to the other of the truck, and a longitudinal partition dividing the main platform into two halves.

3. A truck having a main platform, a pair of uprights secured to each end of the platform, each pair bearing a transverse member adapted to serve as a track, a bracing member extending downwardly from one 90 track to the center of the main platform and thence to the other track, thereby bracing the tracks and also dividing the main platform longitudinally into two halves, and a movable platform mounted on rollers on said 95 tracks and extending between said uprights so as to have a restricted lateral movement across the truck.

HARLEY C. WOOD.
